UNITED STATES PATENT OFFICE

169,349

CONTAINER UNIT FOR DISINFECTANTS, DEODORANTS, INSECTICIDES, AND THE LIKE

Max Antritter, Leicester, Mass., assignor to Van
Brode Milling Co., Inc., Clinton, Mass., a cor-
poration of Massachusetts

Application November 15, 1952, Serial No. 22,315

Term of patent 7 years

(Cl. D16—2)

To all whom it may concern:

Be it known that I, Max Antritter, a citizen of the United States, residing at Leicester, Commonwealth of Massachusetts, have invented a new, original, and ornamental Design for a Container Unit for Disinfectants, Deodorants, Insecticides, and the like, of which the following is a specification, reference being had to the accompanying drawing, forming part hereof.

Fig. 1 is a front elevation of a container unit for disinfectants, deodorants, insecticides, and the like, showing my new design;

Fig. 2 is a side elevation thereof;
Fig. 3 is a rear elevation of the same; and
Fig. 4 is a top plan view thereof.

I claim:

The ornamental design for a container unit for disinfectants, deodorants, insecticides, and the like, as shown.

MAX ANTRITTER.
